INSTRUMENT

Frank H. Hopkins, Fairfield, Conn., assignor to
Manning, Maxwell & Moore, Incorporated,
New York, N. Y., a corporation of New Jersey

Original application July 13, 1940, Serial No.
345,321. Divided and this application April 26,
1941, Serial No. 390,461

2 Claims. (Cl. 240—2.1)

This invention pertains to instruments, for example pressure gauges, dial thermometers or the like, the present application being a division of the copending application for Letters Patent Serial No. 345,321, filed by Frank H. Hopkins, July 30, 1940—the instrument herein chosen for illustration, but without limiting intent, being a pressure gauge of the kind in which a plurality of graduated dials, each with its own individual index or pointer, are so relatively disposed as to be visible from different directions—for instance the case may be provided with a dial at opposite sides (back and front), with the actuating mechanism for both pointers disposed in the space between the dials.

It has previously been proposed to illuminate the dial of such an instrument by means of a lamp or lamps enclosed within the instrument case, for example in a housing provided with an offset chamber at the top or side of the case proper and opening into the case so that the light from the lamp may pass around the edge of the dial and then by reflection from proper surfaces, impinge upon and illuminate the front face of the dial.

The present invention has for its principal object the improvement of instruments of the general class above referred to and in particular to provide such an instrument, whether having a single dial or a plurality of dials, with illuminating means operative to illuminate each dial substantially uniformly and with a soft diffused light.

Other and further objects and advantages of the invention will be pointed out hereinafter in the following more detailed description and by reference to the accompanying drawing in which

Fig. 1 is a front elevation, with certain parts broken away and with certain parts in vertical section, illustrating a multi-dial instrument, for instance a pressure gauge, of the direct reading type, provided with means for illuminating the dials;

Fig. 2 is a vertical section in the vertical plane of the index staffs of the instrument but showing the lamp housing in end elevation; and

Fig. 3 is a fragmentary vertical section substantially on the line 3—3 of Fig. 2.

Referring to Figs. 1, 2 and 3 of the drawing which illustrates one desirable embodiment of the invention, the numeral 1 designates the case of a multi-dial pressure gauge, said case having the side wall 2 which, as here illustrated, is substantially cylindrical and which is open at front and rear. The exterior surface of the case, as

here illustrated, is externally screw threaded for engagement by internal screw threads provided in the cover rings 3 and 4 respectively. The front cover ring 3 has a central aperture in which is fitted the transparent panel 5, while the rear cover ring 4 is furnished with the transparent panel 6. A dial 7 is arranged within the case behind the panel 5, and a second dial 8 is arranged within the case behind the panel 6. While the gauge caps or covers here illustrated are of the usual type, including an outer ring which supports an independent transparent panel, it is to be understood that caps or covers of other type may be employed if desired.

15 The lower part of the case is provided with a platform portion 9 through which is an aperture 10 (Fig. 2) for the accommodation of the stem portion 11 of the movement support. The stem 11 terminates in the externally screw-threaded nipple 12 to which the pressure supply conduit may be attached. The stem 11 is integrally joined to an attaching flange 13 which rests upon the upper surface of the platform 9, to which it is secured by means of screws 14. A boss 15 projects upwardly from the flange 13 and has an internal chamber 16 (Fig. 3) which communicates with the inner end of a passage 17 which leads down through the stem 11 and nipple 12. To the upper part of the boss 15 is secured the lower end of a movement supporting standard 18. This standard, as illustrated in Fig. 2, is preferably narrow in the front-to-rear direction, but has a wide upper portion designed to form a plate-like support to which the gauge movements are secured. The standard 18 is interposed between the front and rear gauge movements. The gauge movements are substantially identical in construction, but are placed back to back, so that the index or pointer of each gauge movement turns in a clockwise direction when viewed through the corresponding transparent panel 5 or 6 respectively.

40 The index staffs 33 and 33^a of the respective gauge movements are in axial alignment, but by reason of the back-to-back location of the movements, and the arrangement of the link and lever connections these two staffs turn in opposite directions, but to the same amount. The pointers or indexers 35 and 25^a are fixed to the outer ends of the respective index staffs and in front of their respective dials, and these dials are provided with stop pins 36 and 36^a respectively to prevent reverse movement of the indexes beyond the zero points of the respective scales. The dials are provided with graduated scales, the

graduations being arranged for direct reading, that is to say, movement of the index or pointer begins at the actual zero of pressure, the movement of the pointer or index over the scale being in direct ratio to the increase in pressure in the chamber 16.

The upper central part of the case of the instrument is provided with an opening 31, Fig. 1, over which is arranged a lamp housing 38. As here illustrated, this housing is of substantially cylindrical elongate contour and is integrally jointed to the wall 2 of the casing—the lamp chamber or space within the housing 38 opening into the space between the two dials 7 and 8.

The opposite ends of this housing 38 are open but normally closed by means of removable and interchangeable end caps. The end cap 39 has a flange 40 which fits against the end of the housing, and the cap is removably held in place by means of wing-bolts 41. The cap 39 is properly shaped and arranged to provide a chamber for the reception of the base of a lamp socket 42, designed to receive a lamp 43 disposed directly above the center of the gauge case. The end member 39 is preferably provided with a downward extension 44 having an internally screw-threaded opening 45 designed to receive the threaded end of a suitable conduit through which electrical conducting wires may enter and be connected to the lamp socket.

The opposite end of the housing 38 is closed by a cap 46 which is normally held to the housing by screws 47.

The dials 7 and 8, are of light transmitting material, preferably translucent, for instance frosted glass, so that light from the space between the dials may pass outwardly through the dials and thus provide a substantially uniform illumination for the scales carried by the exposed surfaces of the dials. As the lamp is housed within the opaque housing 38, its light cannot escape directly forward so as to dazzle the eyes of the observer and thus the illuminated dials are very easy to read. Moreover, the arrangement provides for the use of a lamp of substantial size, so that the chamber between the dials may be flooded with light, thus insuring sufficient intensity of illumination at all points on the dial.

While one desirable embodiment of the invention has herein been illustrated and described, it is to be understood that the invention is not necessarily limited to the precise arrangements herein described, but is to be regarded as broadly inclusive of any and all equivalent constructions such as fall within the scope of the appended claims.

I claim:

1. An instrument of the kind wherein a case,

which houses a gauge movement including an index staff, is provided with a side wall having an aperture therein, and an open-ended lamp housing which bridges said aperture and which is integrally united to the side wall of the case, said housing being substantially cylindrical with its axis perpendicular to the vertical plane of the index staff, the opposite ends of the housing being disposed symmetrically with respect to the vertical mid-plane of the case, the housing having an aperture in its side wall which registers with the aperture in the side wall of the case, the opposite ends of the housing being alike and shaped for the reception of interchangeable closure caps, and interchangeable, removable caps normally closing the opposite ends of the housing, one of said caps being provided with a lamp socket so arranged as to support a lamp within the housing and above said aperture in the side wall of the housing, said latter cap also having an external hollow extension for the accommodation of an electrical conductor leading to the socket.

2. An instrument of the class described comprising a case having a side wall which is open at front and rear, transparent panels normally closing the front and rear of the case respectively, a pair of axially spaced graduated dials within the case, each disposed behind and parallel to one of said transparent panels, an index cooperable with each respective dial, index actuating mechanism, including coaxial index staffs, disposed within the space between the dials, the case supporting an external open-ended lamp housing, said housing being elongate and having its opposite ends disposed at substantially equal distances at opposite sides respectively of the vertical mid-plane of the case and having its longitudinal axis substantially in that vertical plane which is midway between the planes of the dial, the side walls of the case and housing intersecting and integrally merging and having registering openings, the opposite ends of the housing being alike and so constructed and arranged as to accommodate interchangeable end caps, and interchangeable, removable end caps normally closing the opposite ends of the housing, one of said end caps supporting a lamp socket so arranged that a lamp mounted therein is disposed above the index staffs and illuminates the space between the dials, said last-named cap having therein a passage leading from its exterior inwardly to the socket for the reception of a conductor, the dials being of translucent material so that light from the space between the dials may shine through each dial.

FRANK H. HOPKINS.
